UNITED STATES PATENT OFFICE.

SOLOMON RUBY, OF ST. LOUIS, MISSOURI.

DESIGN FOR A HANDLE FOR SPOONS OR SIMILAR ARTICLES.

SPECIFICATION forming part of Design No. 35,091, dated September 17, 1901.

Application filed June 24, 1901. Serial No. 66,892. Term of patent 7 years.

To all whom it may concern:

Be it known that I, SOLOMON RUBY, a citizen of the United States, residing in the city of St. Louis, in the State of Missouri, have invented and produced a new and original Design for the Handle of a Spoon or Similar Article, of which the following is a full, clear, and exact description, reference being had to the accompanying drawing, forming part of this specification.

The drawing shows a handle of my new design.

As shown in the drawing, the leading or material feature of my design consists in the handle, the outer end of which is formed by the characters "1903," below which are bulg-

ing portions, each successive one of which increases in dimensions, beginning with the narrowest at the innermost part of the handle and ending with the widest at the outer end. 20

The design herein set forth is intended for use as the handle of handled articles of various descriptions, such as a spoon or fork.

I claim as my invention—

The design for the handle of a spoon or similar article, herein shown and described.

SOLOMON RUBY.

In presence of—

E. S. KNIGHT,
M. P. SMITH.
